DRIVING MECHANISM FOR PRODUCING
GYRATORY MOVEMENTS

George H. Hebebrand, Berkley City, Mo.

Application July 30, 1947, Serial No. 764,866

7 Claims. (Cl. 74—87)

1

This invention relates to driving mechanisms for producing gyratory movement of suspended bodies, sifters of sifting machines, for instance, the predominant object of the invention being to provide a gyratory driving mechanism which is of such improved construction and arrangement that sifters of sifting machines may be subjected to gradually increasing gyratory movement at the beginning of a sifter driving operation and to gradually diminishing gyratory movement at the end of the sifter driving operation after power is cut off and thus avoid production of erratic movement of the sifters or movement thereof beyond the limits of their normal zone of operation.

In the type of driving mechanism to which this invention relates in which pivotally supported weight means serves to unbalance the driving mechanism and produce the desired gyratory movement, many of the prior drives possessed the disadvantage of producing wide, circular movements of sifters with which the drives were associated both in starting and stopping the drives. This was due to the fact the unbalancing weight means of these earlier drives would start to swing outwardly as soon as revolution thereof was started, and as the weight means was quite heavy, there was a tendency for the sifters to move in circular paths in unison with the weight means, instead of opposing movement thereof, thereby throwing the sifters beyond their normal paths of movement and frequently doing damage to the sifting machines. The foregoing was true, also, when power was cut off preparatory to stopping a sifting machine equipped with one of these earlier gyratory drives, the momentum of the weight means decreasing until the movement thereof was substantially synchronized with the movement of the sifter, whereupon their rotating weight means would tend to swing the sifter in a wide circular path causing said sifter to move beyond the limits of its normal zone of movement.

The above-mentioned disadvantages are eliminated in the use of the gyratory drive disclosed herein wherein the weights are so mounted and arranged that when at rest their center of gravity substantially coincides with the center of gravity of the associated sifter. As a result of this situation, the weights, at the beginning of a driving operation, will have acquired a relatively high speed of rotation before they start to move outwardly, and when this outward movement of the weights is started said displaced weights immediately throw the sifter off center

2

so that in each cycle of movement thereafter, the outward throw of the sifter box will oppose the outward throw of the weights. In like manner, when power is cut off preparatory to stopping the sifting machine and the weights approach their retracted positions, they tend to rotate in a substantially balanced manner with the main drive shaft of the sifting machine with practically no tendency to throw the sifter off center, whereby the sifter is brought to rest gradually and by an even movement.

Extremely important features of the present invention have to do with the manner in which the weights are caused to swing outwardly in unison in the operation of the improved driving mechanism, and the manner in which the weights are caused to return to their retracted positions when the speed of rotation of the driving mechanism diminishes after the power has been cut off preparatory to arresting operation of the driving mechanism.

Fig. 1 is a side elevation showing the improved driving mechanism of the present invention applied to a plan sifter, the supports for the latter being broken away.

Fig. 2 is a fragmentary, horizontal section taken on line 2—2 of Fig. 1.

Fig. 3 is an enlarged, horizontal section taken on line 3—3 of Fig. 1.

Fig. 4 is an elevational view of part of the driving mechanism of the present invention.

Fig. 5 is a perspective view of a receptacle forming part of one of the weight structures of the improved driving mechanism of the present invention.

Fig. 6 is an enlarged, horizontal section taken on line 6—6 of Fig. 1.

In the drawings, wherein is shown for purposes of illustration, merely, one embodiment of the invention, A designates a plan sifter which, as usual, is supported from the ceiling, or other support, by sets of wooden rods, or reeds, B. The plan sifter A is comprised of a pair of spaced apart boxes C wherein sieves (not shown) are arranged in the usual manner, the sets of wooden rods, or reeds, B being secured to said boxes. Disposed in the space between the boxes C is a gyratory driving mechanism I which is constructed and arranged in accordance with the present invention, said driving mechanism including a pair of vertically spaced bearing structures 2 which are secured at their opposite ends to walls of the boxes C and which are provided with vertically aligned bearings 3 that support for rotation the main shaft 4 of the plan sifter A. Fix-

edly mounted on the main shaft 4 is a pulley 5 about which a transmission belt 6 operates for rotating said pulley 5 and said main shaft 4, said transmission belt operating, also, about a pair of smaller pulleys 7 which are supported for rotation by the boxes C, and about a pulley which may be supported by an overhead power shaft (not shown).

Supported by the main shaft 4 is a secondary shaft 8 which is arranged parallel with respect to said main shaft. The secondary shaft is fixed to the main shaft so that it rotates therewith about the axis of said main shaft, the means employed for attaching said secondary shaft to said main shaft comprising a pair of brackets 9 and 10 which are spaced vertically, as is shown in Fig. 1. The brackets 9 and 10 are of like construction and arrangement, each of said brackets comprising a split clamping structure (see Fig. 6) which is composed of a pair of members 11 that are recessed to receive the shafts 4 and 8 and which are drawn together by bolts 12 so that they clampingly engage said shafts for secure attachment thereto.

The gyratory driving mechanism 1 of the present invention includes a pair of weight structures 13 and 14 which are supported by the secondary shaft 8 for pivotal movement thereabout. Each weight structure comprises a vertically elongated receptacle which is closed at the bottom and open at the top, the main body of each receptacle being formed from sheet metal, or other suitable material, and edges of the material of which the receptacle is formed being welded, or otherwise secured to a bar 15 which extends from top to bottom of the receptacle. The receptacle of each weight structure 13 or 14 is provided with a vertically spaced pair of tubular bearing members, the bearing members of the receptacle of the weight structure 13 being designated by the reference character 16 and being located immediately at the top and bottom of the receptacle, while the bearing members of the receptacle of the weight structure 14 are designated by the reference character 17 and are located inwardly of the top and bottom of said receptacle. The tubular bearing members 16 and 17 of the receptacles of the weight structures 13 and 14 are welded, or otherwise secured, to the bars 15 of the respective receptacles. The receptacles of the weight structures receive therein weights formed of lead, or other material, which provide the weight structures with the desired weight.

The secondary shaft 8 extends loosely through the bearing members 16 and 17 of the receptacles of the weight structures 13 and 14 whereby said receptacles may rotate about said secondary shaft from the positions in which said receptacles are shown by full lines in Fig. 3 to the dotted line positions of said receptacles as shown in that view. When the gyratory driving mechanism is at rest the lowermost bearing member 16 of the receptacle of the weight structure 13 rests on the top face of the bracket 10, as is shown in Fig. 1, while the lowermost bearing member 17 of the receptacle of the weight structure 14 rests on the top face of said lowermost bearing member 16 of the receptacle of said weight structure 13. Also, the upper bearing member 17 of the receptacle of the weight structure 14 underlies the upper bearing member of the receptacle of the weight structure 13, as is also shown in Fig. 1. It is to be noted, also, that when the gyratory driving mechanism is at rest the tops of the weight structures are spaced downwardly a con-

siderable distance from the lower face of the bracket 9.

The secondary shaft 8 has fixedly mounted thereon a tubular element 18 which is located between the tubular bearing members 17 of the receptacle of the weight structure 14, as is shown in Fig. 1, the uppermost of said tubular bearing members 17 resting on the top edge of said tubular element 18 when the gyratory driving mechanism is at rest. The tubular element 18 has formed in the wall thereof a pair of opposed slots 19 and 20, said slots being of partial helical formation, as is shown to good advantage in Fig. 4. The slot 19 of the tubular element 18 receives a shoe 21 that is fixed to a pin 22 which is supported for rotary movement in an opening formed in the bar 14 of the receptacle of the weight structure 13. In like manner, the slot 20 of the tubular element 18 receives a similar shoe 23 that is fixed to a pin 24 which is supported for rotary movement in an opening formed in the bar 15 of the receptacle of the weight structure 14.

In describing the operation of the gyratory driving mechanism disclosed herein attention is first directed to the fact that the receptacles of the weight structures 13 and 14 are shaped in horizontal section as is shown in Fig. 3. In other words, the receptacles referred to are provided with substantially V-shaped depressions 25 that extend from top to bottom of said receptacles and which, when the weight structures are at rest, cooperate to provide a space through which the main shaft 4 of the driving mechanism 1 extends, said space being maintained by contact of corner portions of the receptacles as indicated at 26 in Fig. 3. As a result of the arrangement of the weight structures relative to the main shaft 4, as shown in Fig. 3, the weight of the gyratory driving mechanism is distributed about the main shaft in a substantially balanced manner when the weight structures 13 and 14 are at rest, and, therefore, the center of gravity of the weight structures 13 and 14 substantially coincides with the center of gravity of the associated plan sifter.

When the improved gyratory driving mechanism is set in motion to impart gyratory motion to the associated plan sifter A, the main shaft 4 and the weight structures 13 and 14 associated therewith rotate during an initial period of operation of the gyratory driving mechanism in a substantially balanced manner. However, when the required rate of speed of operation of the driving mechanism is attained, centrifugal force 55 overcomes the pull of gravity and the weight structures 13 and 14 swing outwardly about the secondary shaft 8, the presence of the shoes 21 and 23 in the slots 19 and 20 of the tubular element 18 causing said weight structures to simultaneously move upwardly and said shoes moving longitudinally of the slots. The weight structures 13 and 14 will eventually reach the positions in which they are shown by dotted lines in Fig. 3 where corner portions of said weight structures 65 contact as indicated at 27 in said view. As the weight structures 13 and 14 move outwardly and upwardly, a gradual unbalancing of the driving mechanism occurs which subjects the plan sifter A to gradually increased gyratory motion, the 70 intensity of this gyratory motion of the plan sifter increasing gradually until the weight structures 13 and 14 reach the maximum unbalanced positions in which they are shown by dotted lines in Fig. 3. Thereafter the plan sifter is subjected 75 to uniform gyratory motion throughout the sifter.

ing operation with the weight structures 13 and 14 in their positions of greatest displacement, and when the sifting operation has been completed and the power has been shut off the reduced speed of rotation of the driving mechanism will cause the pull of gravity to overcome centrifugal force so as to permit the weight structures to move downwardly, whereby the shoes 21 and 23 moving longitudinally of the slots 19 and 20 of the tubular element 18 will return the weight structures to their positions of rest, as illustrated by full lines in Fig. 3, to cause the final portion of the operation of the drive mechanism to be performed in a balanced manner.

It is obvious, therefore, that the gyratory drive mechanism of the present invention operates in a balanced manner at the beginning of an operation until sufficient speed of operation is attained to cause the weight structures to swing outwardly and upwardly. Thereafter, the maximum gyratory motion is imparted to the plan sifter throughout the sifting operation, and after the power is cut off and the speed of operation of the drive mechanism has been reduced sufficiently, the weight structures move downwardly and are returned to their positions of rest through cooperation of the shoes 21 and 23 and the slots 19 and 20 of the tubular element 18, to cause the drive mechanism to come to rest while again operating in a balanced manner. Thus, in the operation of the drive mechanism disclosed herein the objectionable wide swinging of the plan sifter at beginning and at the end of an operation are entirely eliminated whereby a more efficiently operating structure is provided.

It has been stated herein that the lowermost bearing member 16 of the receptacle of the weight structure 13 underlies the lowermost bearing member 17 of the receptacle of the weight structure 14, and that the uppermost bearing member 17 of the receptacle of said weight structure 14 underlies the uppermost bearing member 16 of the receptacle of the weight structure 13. As a result of this situation said receptacles of said weight structures are compelled to operate in unison when they swing outwardly and move upwardly, as upward movement of either of said receptacles will subject the other receptacle to corresponding upward movement, which will be translated into rotary movement by cooperation of the shoes 21 and 23 and the slots 19 and 20 of the tubular element 18.

I claim:

1. A driving mechanism for producing gyratory movement of a suspended body, comprising a main shaft supported for axial rotation, a secondary shaft supported by said main shaft for rotary movement therewith about the axis of said main shaft, a pair of weight structures which are both supported by said secondary shaft for rotary movement thereabout and swingable by centrifugal force from positions where said weight structures are substantially balanced relative to said main shaft to positions where said weight structures are unbalanced with respect to said main shaft, and means supported by said secondary shaft for returning said weight structures from unbalanced positions with respect to said main shaft to balanced positions relative thereto.

2. A driving mechanism for producing gyratory movement of a suspended body, comprising a main shaft supported for axial rotation, a secondary shaft supported by said main shaft for rotary movement therewith about the axis of said main shaft, a pair of weight structures which

are both supported by said secondary shaft for rotary movement thereabout and swingable by centrifugal force from positions where said weight structures are substantially balanced relative to said main shaft to positions where said weight structures are unbalanced with respect to said main shaft, and means supported by said secondary shaft for returning said weight structures from unbalanced positions with respect to said main shaft to balanced positions relative thereto, said means comprising an element fixed to said secondary shaft and provided with a pair of guideways, and elements carried by said weight structures which are movable respectively in said guideways.

3. A driving mechanism for producing gyratory movement of a suspended body, comprising a main shaft supported for axial rotation, a secondary shaft supported by said main shaft for rotary movement therewith about the axis of said main shaft, a pair of weight structures which are both supported by said secondary shaft for rotary movement thereabout and swingable by centrifugal force from positions where said weight structures are substantially balanced relative to said main shaft to positions where said weight structures are unbalanced with respect to said main shaft, and means supported by said secondary shaft for returning said weight structures from unbalanced positions with respect to said main shaft to balanced positions relative thereto, said means comprising an element of tubular formation fixed to said secondary shaft and provided with a pair of guideways, and elements carried by said weight structures which are movable respectively in said guideways.

4. A driving mechanism for producing gyratory movement of a suspended body, comprising a main shaft supported for axial rotation, a secondary shaft supported by said main shaft for rotary movement therewith about the axis of said main shaft, a pair of weight structures which are both supported by said secondary shaft for rotary movement thereabout and swingable by centrifugal force from positions where said weight structures are substantially balanced relative to said main shaft to positions where said weight structures are unbalanced with respect to said main shaft, and means supported by said secondary shaft for returning said weight structures from unbalanced positions with respect to said main shaft to balanced positions relative thereto, said means comprising an element of tubular formation fixed to said secondary shaft and provided with a pair of guideways of partial helical configurations, and elements carried by said weight structures which are movable respectively in said guideways.

5. A driving mechanism for producing gyratory movement of a suspended body, comprising a main shaft supported for axial rotation, a secondary shaft supported by said main shaft for rotary movement therewith about the axis of said main shaft, a pair of weight structures which are both supported by said secondary shaft for rotary movement thereabout and swingable by centrifugal force from positions where said weight structures are substantially balanced relative to said main shaft to positions where said weight structures are unbalanced with respect to said main shaft, and means supported by said secondary shaft for returning said weight structures from unbalanced positions with respect to said main shaft to balanced positions relative thereto, said means comprising an element of

tubular formation fixed to said secondary shaft and provided with a pair of slots forming guideways of partial helical configurations, and elements carried by said weight structures which are movable respectively in said guideways.

6. A driving mechanism for producing gyratory movement of a suspended body, comprising a main shaft supported for axial rotation, a secondary shaft supported by said main shaft for rotary movement therewith about the axis of said main shaft, a pair of weight structures which are both supported by said secondary shaft for rotary movement thereabout and swingable by centrifugal force from positions where said weight structures are substantially balanced relative to said main shaft to positions where said weight structures are unbalanced with respect to said main shaft, and means supported by said secondary shaft for returning said weight structures from unbalanced positions with respect to said main shaft to balanced positions relative thereto, said means comprising an element of tubular formation fixed to said secondary shaft and provided with a pair of slots forming guideways of partial helical configurations, and pivotally supported elements carried by said weight structures which are movable respectively in said guideways.

7. A driving mechanism for producing gyratory movement of a suspended body, comprising a main shaft supported for axial rotation, a secondary shaft supported by said main shaft for rotary movement therewith about the axis of said main shaft, a pair of weight structures supported

by said secondary shaft for rotary movement thereabout and swingable by centrifugal force from positions where said weight structures are substantially balanced relative to said main shaft to positions where said weight structures are unbalanced with respect to said main shaft, said weight structures comprising each a receptacle which receives therein weight-producing matter, and each of said receptacles being provided with bearing members which embrace said secondary shaft in such relation that a bearing member of each weight structure underlies a bearing member of the other weight structure, and means supported by said secondary shaft for returning said weight structures from unbalanced positions with respect to said main shaft to balanced positions relative thereto.
